INVENTOR,
Elliott Carns,
By *M. D. Hall*
ATTORNEY.

UNITED STATES PATENT OFFICE.

ELLIOTT CARNS, OF SOUTH BOSTON, MASSACHUSETTS, ASSIGNOR TO DAYTON SCALE COMPANY, OF DAYTON, OHIO, A CORPORATION OF NEW JERSEY.

COMMINUTING OR GRINDING MACHINE.

Application filed February 18, 1924. Serial No. 693,613.

To all whom it may concern:

Be it known that I, ELLIOTT CARNS, a citizen of the United States, residing at South Boston, in the county of Suffolk and State of Massachusetts, have invented certain new and useful Improvements in Comminuting or Grinding Machines, of which the following is a specification.

This invention relates to a comminuting or grinding machine primarily for food products.

An important aim is to provide a means whereby the discharge end construction of the bowls of existing machines, particularly those having exterior screw threads for attachment of an end ring thereto, will be rendered and kept more sanitary, may be opened and closed easier and rapidly, and the user will be encouraged to more frequently clean the same to thus particularly adapt said existing bowls for application thereto of the improvements disclosed in my Patent 1,498,262, covering an improvement in comminuting or grinding machines, issued June 17, 1924, and to also adapt said existing bowls for application thereto of improved end ring constructions generally, particularly those rendering operation easier and more rapid and promoting sanitation, to the end that all of the objects and advantages, as well as those otherwise peculiar to the present invention, set forth in the said patent may be realized.

Another object is to provide a construction wherein an adapter collar is used which covers the screw threads of the bowl and which removes foreign matter from such threads incidental to its application thereto, and will prevent entrance of foreign matter between the bowl and collar when the latter is in place.

A further object is to provide a construction wherein the adapter collar has means rigid, preferably integral, therewith and constituting part of separable connecting means for the replacement end ring to reinforce the collar and be capable of use as abutments for the fingers of the operator when applying the adapter collar to the bowl.

Various additional objects and advantages will become apparent, some being further pointed out, from a consideration

of the description following taken in connection with accompanying drawings illustrating an operative embodiment. 55

In said drawings:

Figure 1 is a side elevation showing the improvements applied to a bowl;

Figure 2 is an end elevation looking 60 toward the discharge end of the bowl;

Figure 3 is a fragmentary side elevation, partly in section, illustrating details of the end construction of the bowl;

Figure 4 is a front elevation of the 65 adapter collar;

Figure 5 is an edge elevation of the adapter collar and

Figure 6 is a vertical sectional view 70 through the replacement end ring.

Referring specifically to the drawing wherein like reference characters designate like or similar parts in the different views thereof, bowl A is of conventional construction, consisting primarily of a supply hopper B leading to a barrel or cylinder C whose axis is horizontally disposed. Within cylinder C, a usual feed screw and cutter or the equivalent (not shown) and a perforated plate D are removably disposed. On barrel or cylinder C adjacent the discharge end are exterior screw threads E adapted for threaded engagement as usual by an ordinary end ring (not used or shown). 75

In place of the ordinary end ring, an 80 adapter collar 13 is employed which has interior screw threads 14 to removably engage and completely cover those at E. Collar 13 may be a casting with the threads 14 thereof appropriately machined, if desired. Said collar 13 has any suitable number of outwardly radiating lugs 15 usually integral therewith at a distance inwardly of the discharge or end of the barrel where plate D is located. Lugs 15 loosely and detachably carry the shanks of bolts 16 having heads 17 and on which nuts 18, as of the wing type to facilitate finger manipulation are employed. The adapter collar 13 between lugs 15 and the remote end thereof has a truly cylindric surface 19. Lugs 15 serve as abutments for the fingers of the operator's hand in the acts of applying and removing the adapter collar. 85

The end ring used as a replacement or substitute for the ordinary or discarded end 90

ring is generally designated 20, and may be identical in construction with that disclosed in my Patent 1,498,262 aforesaid, although the construction does and it is an object to accommodate all improved forms of end rings, particularly those designed to render operation easier, more rapid and which increase sanitation. This ring may be a single metallic casting generally of L-shape in cross section so as to have a relatively wide annular wall 21 and an inwardly extending flange 22 at its outer marginal edge. Adjacent the inner marginal edge, outwardly extending hook lugs 23 are provided equal in number and spaced similarly to lugs 15. Said lugs 23 are of considerably less thickness than the width of the end ring 20 so that the heads 17 will as shown in Figure 1 be located a considerable distance inwardly 70 of the flange or outer end of the ring in order not to interfere with manual engagement or gripping of said ring. Lugs 23 have arcuate slots 24 to receive the bolts 16. The wall 21 in line with lugs 23 has exterior depressions 25 which serve as finger-holds and also enable the bolts 16 and lugs 23 to be located closer to the center of the end ring, resulting in a more compact construction.

15 I may use a suitable number of relatively small teats 26 on cylinder C, for instance equidistantly between and of the same number as lugs 15. The inner surface of wall 21 has shallow L-shaped slots 27 as in said 75 allowed application or shallow substantially Z-shaped slots 27 as disclosed herein. Said teats 26 and slots 27 serve to properly guide end ring 20 in its application to the cylinder and also serve to supplement the action of 80 bolts 16 in resisting longitudinal outward pressure on the end ring.

40 In use, the usual end ring is removed and discarded and my adapter ring 13 is manually grasped and threaded onto the cylinder C with the fingers disposed between and abutting lugs 15 for increased leverage. The threads 14 during this movement dislodge and remove all obstructions or foreign matter from the threads E insuring a clean 45 and sanitary connection between the adapter ring and bowl. Sanitation is further assured as the adapter collar 13 completely covers and encloses the threads 14 against entrance of foreign matter between the 50 adapter collar and cylinder C. The end ring 20 is grasped manually with fingers of one hand of the operator disposed in the depressions 25, and then applied longitudinally 55 onto the wall 19 with slots 27 in registry with and receiving teats 26, after which by 60 rocking motion of the end ring on the surface 19 as a bearing the slots 24 of hook lugs 23 will engage the shanks of bolts 16 and the teats will reach substantially the inner ends of slots 27. Wing nuts 18 are then 65

tightened. Adapter ring 13 is designed to permanently but removably remain applied to the bowl but the end ring 20 is adapted for frequent removal, as in said Patent 1,498,262, and the user is encouraged to clean the machine oftener and keep it in a sanitary condition, which while a desideratum in connection with the grinding of meat in particular is a well known matter of neglect under 75 present conditions.

75 Various changes may be resorted to provided they fall within the spirit and scope of the invention.

I claim as my invention.

1. In combination with the bowl of a comminuting machine or the like, an adapter means applicable thereto, and a replacement end ring different in structure from the original end ring of the machine associated with said means.

80 2. In combination with the bowl of a comminuting machine or the like having means for attachment of an end ring thereto, an adapter means applicable to the first mentioned means to cover the same in the aid 85 of sanitation, and an end-ring-replacing means different in structure from the original end ring of the machine carried by the adapter means.

90 3. In combination with the bowl of a comminuting machine or the like having means for attachment of an end ring thereto, an adapter means applicable to the first mentioned means constructed to clean the latter through application thereto and to cover 95 the same in the aid of sanitation, and an end-ring-replacing means different in structure from the original end ring of the machine carried by the adapter means.

100 4. In combination with the bowl of a comminuting machine or the like having means for attachment of an end ring thereto, an adapter means applicable to the bowl and of a size to cover the first mentioned means in the aid of sanitation, and an end-ring-replacing means different in structure from the original end ring of the machine associated with the adapter means.

110 5. In combination with the bowl of a comminuting machine or the like having screw threads for attachment of an end ring thereto, an adapter means provided with screw threads applicable to said screw threads for connection to the bowl and to clean the first screw threads and to cover them in the aid 115 of sanitation, and an end-ring-replacing means different in structure from the original end ring of the machine associated with the adapter means.

120 6. In combination with the bowl of a comminuting machine or the like, an adapter means applicable thereto, an end-ring-replacing means associated with the adapter means, and means of detachable connection between the first and second mentioned 125

means having a part serving as a finger abutment for application and removal of the adapter means.

7. In combination with the bowl of a comminuting machine or the like, an adapter applicable thereto, an end-ring-replacing means, lugs extending from the adapter serving as finger abutments during application and removal thereof, and connections 10 between said lugs and end-ring-replacing means.

8. In combination with the bowl of a comminuting machine or the like provided with screw threads for attachment of an end ring thereto, an adapter collar having screw threads engaging said screw threads, lugs extending from the adapter serving as finger abutments during application and removal thereof, a replacement end ring telescopically engageable with said adapter collar, and connection between said lugs and replacement end ring.

9. An adapter collar of the class described having interior screw threads for at-

tachment to a bowl, and lugs extending outwardly therefrom to serve as finger abutments and for connection of an end ring thereto.

10. An adapter collar of the class described having means on its interior to clean screw threads of a bowl incidental to application thereto, and end-ring-attaching and finger-abutment lugs extending outwardly from the collar.

11. An adapter collar of the class described having screw threads on its interior for attachment to a bowl and to clean screw threads of a bowl incidental to application thereto, the outer surface at a portion thereof being cylindric to receive a replacement 40 end ring telescopically, and end-ring-attaching and finger-abutment lugs extending outwardly from the collar and inwardly of said portion.

In testimony whereof I have affixed my 45 signature.

ELLIOTT CARNES.
